ABRAHAM J. R. MACDOUGALL, OF BROOKLYN, NEW YORK.

MOVING-PICTURE MACHINE.

1,196,709.

Specification of Letters Patent. Patented Aug. 29, 1916.

Application filed August 9, 1913. Serial No. 783,880.

To all whom it may concern:

Be it known that I, ABRAHAM J. R. MACDOUGALL, a citizen of the United States of America, residing at 159 Newell street, Brooklyn, New York, have invented new and useful Improvements in Moving-Picture Machines, of which the following is a specification.

This invention relates to moving picture machines and more particularly to safety devices for preventing the film from catching fire during the operation of the machine.

One of the objects of the invention is to provide means for preventing the film from catching fire if the film breaks or if the feeding of the film is not uniform.

Another object of the invention is to provide a device of this character which may be readily placed in position upon moving picture machines such as are now in use.

Another object is to provide a device of this character which is cheap to manufacture, which is simple in construction and operation and which is not likely to get out of order.

Other objects will in part be obvious and in part be pointed out hereinafter.

In the accompanying drawings showing an illustrative embodiment of this invention and in which the same reference numerals refer to similar parts in the several figures, Figure 1 is a vertical sectional view of the device, part of a moving picture machine being indicated for the sake of clearness. Fig. 2 is a view in rear elevation of the device. Fig. 3 is a detail view of the upper part of the device in front elevation. Fig. 4 is a sectional view taken on the line 4-4 of Fig. 2.

In the illustrative embodiment of the invention shown in the drawings, 1 represents the casing of a moving picture machine of any suitable construction, provided with feeding and guiding devices 2, by means of which the film 3 is fed and guided from one magazine to the other in the usual manner. 4 represents the well known shutter which is adapted to close automatically when the speed of the feeding mechanism drops below a certain predetermined limit. As this shutter may be of any known type, further illustration is unnecessary. Shutters of this character are effectual for preventing the film from catching fire when the speed of the feeding mechanism drops below a certain limit, but

in cases where the film breaks, or is unevenly fed for any reason, and at which time the speed of the feeding mechanism does not drop below the predetermined limit, a shutter of this type will not act to prevent the film from catching fire, as it will be held open by reason of the fact that the mechanism is running at its regulation speed. The danger of the film catching fire by reason of its breaking or its uneven feeding is overcome by the device constructed in accordance with this invention, and which will now be described.

5 represents a casing of any suitable conformation adapted to be held in position between the source of light and the film in any suitable manner, preferably by supporting it on the machine casing. The casing 5 is provided with an aperture 6 through which the light from the source of illumination passes to the film, and which aperture is in registry with the aperture controlled by the speed-controlled shutter 4. A shutter 7 is pivotally mounted upon the casing 5 and is normally held closed in any suitable manner, as by gravity. Operatively connected to the shutter 7 is an arm 8 with which one end of the arm 9 of a bent lever 10 is adapted to engage. The casing 5, is, as shown in the drawing, provided with a slot 11 through which the end of the arm 9 extends as clearly illustrated in Fig. 1. The bent lever 10 is pivotally supported in any suitable manner and adjacent its lower end it is provided with a transversely extending portion carrying a roller 12 which rotates freely thereon.

The lever 10 normally occupies the position indicated in dotted lines in Fig. 1, in which position the end of the arm 9 is drawn backward, thus allowing the shutter 7 to fall and close the aperture 6. When the film is passed through the feeding mechanism, however, it will engage the roller 12 and due to the tension of the film the lever 10 will be forced to occupy the position shown in full lines in Fig. 1, in which position the end of the arm 9 will, by co-acting with the arm 8, hold the shutter 7 in its open position, thereby permitting the rays of light to pass through the aperture 6. As the roller 12 against which the film engages, rotates loosely upon the lever 10 there will be no wear on the film as of course there will be no friction between it and the roller.

As long as the film remains intact and is

fed properly the tension of the same will hold the lever 10 in this position. If the film should break, or if for any reason the feeding of the film becomes irregular, the pressure of the film against the roller 12 will cease and the lever 10 will then, through gravity, assume its normal position indicated in dotted lines in Fig. 1, allowing the shutter 7 to drop and intercept the rays of light which pass through the aperture 6, thus preventing the film from catching fire.

By employing this shutter in connection with the usual speed regulated shutter it will be seen that the danger of the film catching fire is reduced to a minimum. If the speed of the feeding mechanism drops below the predetermined value, the shutter 4 will automatically close, while if, on the other hand, the speed does not drop below the predetermined value, but the feed of the film becomes irregular or the film breaks, the shutter 7 will automatically close. In either case, therefore, the rays of light which pass from the source of illumination to the film will be intercepted.

Having described this invention in connection with the illustrative embodiment thereof to the details of which disclosure the invention is of course not to be limited, what is claimed as new and what is desired to be secured by Letters Patent is set forth in the appended claims:

1. In a moving picture machine, in combination, a swinging fire shield suspended normally from a horizontal pivotal axis in operative position interposed between the source of light and the film to intercept the rays of light, and a movable member adapted to contact with a stretch of the film when under normal tension to be maintained thereby in operative position and adapted to move automatically into inoperative position when released by a slack occurring in

the film, a portion of said member being disposed in the path of movement of a part of the shield below its pivotal axis and adapted upon movement of the said member into operative position to force the shield into tilted inoperative position resting upon said member.

2. In a moving picture machine, in combination, a swinging fire shield suspended normally from a horizontal pivotal axis in operative position interposed between the source of light and the film to intercept the rays of light, said shield having an arm offset angularly with respect to the shield proper, and a movable member adapted to contact with a stretch of the film when under normal tension to be maintained thereby in operative position wherein it contacts with the shield arm at a point situated below its pivotal axis to support the shield in tilted inoperative position.

3. In a moving picture machine, in combination, a swinging fire shield suspended normally from a horizontal pivotal axis in operative position interposed between the source of light and the film to intercept the rays of light, and a pivoted member having two arms, one of said arms being adapted to contact with a stretch of the film when under normal tension to maintain the said member in operative position wherein its other arm is disposed in the path of movement of a part of the shield and contacts with the same at a point below its pivotal axis and supports it in tilted inoperative position.

In testimony whereof I have signed my name to this specification in the presence of two subscribing witnesses.

ABRAHAM J. R. MACDOUGALL.
